UNITED STATES PATENT OFFICE.

OTTO FRICKE, OF NEW YORK, N. Y.

MAST FOR WIRELESS TELEGRAPHY.

1,026,388.

Specification of Letters Patent.

Patented May 14, 1912.

Application filed February 20, 1912. Serial No. 678,758.

To all whom it may concern:

Be it known that I, OTTO FRICKE, a citizen of the German Empire, residing in New York, in the borough of the Bronx, county 5 and State of New York, have invented certain new and useful Improvements in Masts for Wireless Telegraphy, of which the following is a specification.

This invention relates to an improved 10 mast for wireless telegraph stations by which the mast and the antennæ supported on the same are protected in an effective manner against wind-pressure.

It was found necessary heretofore, especially 15 in stormy weather, to lower the antennæ of wireless telegraph stations from the mast so as to prevent damage and injury to the same. This, however, had the disadvantage of temporarily interrupting the wire- 20 less telegraphic intercourse between stations on land and on vessels and between the stations on the vessels themselves.

The object of this invention therefore is 25 to overcome this objection and to provide in addition to the main-mast a yielding or pendulum-mast, by which the mast is less injuriously exposed to wind-pressure, the lowering of the antennæ in stormy weather obviated, and the safety and reliability 30 of wireless intercourse greatly increased, and in addition thereto, a considerable saving in the construction expenses of such masts obtained; and for this purpose the invention consists of a mast for wireless 35 telegraph stations which comprises a main or foundation-mast and an auxiliary or pendulum-mast supported on the apex or terminal of the main-mast and balanced thereon by means of counter-weights applied to 40 arms of the pendulum-mast extending downwardly to some distance below the apex of the main-mast.

In the accompanying drawings, Figure 1 45 represents a side-elevation of the upper part of my improved mast for wireless telegraph stations. Fig. 2 is a diagrammatic plan-view of the mast and the guy-ropes for the main-mast, and Fig. 3 is a detail vertical central section, drawn on a larger scale 50 through the upper end or apex of the main-mast and the lower end of the auxiliary or pendulum-mast.

Similar letters of reference indicate corresponding parts throughout the several figures 55 of the drawings.

Referring to the drawings, 5 represents

the main or foundation-portion of my improved mast for wireless telegraph stations. The main-portion 5 is constructed preferably of open iron girder-work and supported 60 by means of guy-ropes 6 in connection with suitable foundations 8 in the usual well-known manner. The main-portion 5 is provided at its upper end with a solid apex or terminal 4, as shown in Fig. 3, which terminal is preferably insulated by suitable insulating material and provided with a concave depression at its upper end in which is supported the auxiliary or pendulum-portion 1 of the mast by its rounded off lower 70 end or terminal 7.

The auxiliary or pendulum-mast 1 is made of open girder-work in the same manner as the main-mast and provided with outwardly inclined and downwardly-extending 75 arms 2, which extend below the point of support 4 of the main-section 5 and which are provided at their lower ends with counter-balancing weights 3 that are preferably made of cylindrical shape and filled with a 80 non-freezable liquid, such as, glycerin, or other heavy material, so that the pendulum-mast 1 is balanced on the apex of the main-mast whatever may be the position of the pendulum-mast under the wind-pressure 85 thereon. The upper end of the pendulum-mast is provided with a lightning-rod and with means for suspending the antennæ 9 from the same. The auxiliary or pendulum-mast 1 follows the direction of the wind 90 and assumes a more or less inclined position relatively to the vertical axis of the main-mast according to the greater or less strength of the wind-pressure. By the variable inclination of the pendulum-mast, the 95 necessity of lowering the antennæ during stormy weather is entirely obviated, while by the use of the pendulum-mast the height of the entire mast can be increased so that the antennæ can be supported, especially 100 when on board of steamers or other vessels, at a higher elevation than that of the ordinary masts of the vessels so as not to interfere with the same.

In place of the two downwardly-extending and counter-balanced arms of the pendulum-mast 1, four arms may be arranged, a second pair being located at right angles to the first pair of counter-weighted arms.

The advantages of my improved construction of masts for wireless telegraph stations are first, that the main-mast and its

2
 guy-ropes can be made much shorter and erected at much less expense than heretofore, as the auxiliary or pendulum-mast does not require any special wind-bracing; second, 5 that the auxiliary or pendulum-mast can be made much lighter than the upper ends of the masts at present in use; third, that as the force of the air-pressure is taken up by the pendulum-mast which follows in its oscillations the direction and strength of the wind, and as the pendulum-mast only acts by gravity in the direction of the axes of the main-mast, a much lighter and less expensive construction of the main-mast can be 10 employed and as the same is not impaired by wind-pressure, also a vastly more effective mast for wireless telegraph stations obtained.

The construction of the auxiliary or pendulum-mast can also be used for protecting the upper ends of church-spires against the destructive action of the wind-pressure on the same, the spires being divided in an analogous manner into a stationary main- 20 portion and a counter-balanced auxiliary or pendulum-portion. The same principle can also be applied to metallic smoke-stacks so that the height of these stacks can be increased and the pendulum-portion protects 25 them to a considerable extent against the damaging effect of wind-pressure.

I claim:

1. A mast for wireless telegraph stations, comprising a main or foundation-mast, and a counterbalanced auxiliary or pendulum- 35 mast supported on the apex of the main-mast.

2. A mast for wireless telegraph stations, comprising a main or foundation-mast having a terminal bearing at its apex, and an auxiliary or pendulum-mast supported on 40 said terminal bearing and being provided with downwardly-extending arms having counter-balancing weights at their lower ends.

3. A mast for wireless telegraph stations, comprising a main or foundation-mast, having a concave bearing at its apex, and an auxiliary or pendulum-mast having a rounded off lower end supported on said 45 concave bearing, said pendulum-mast being provided with outwardly-inclined downwardly-extending arms having counter-balancing weights at their lower ends.

In testimony, that I claim the foregoing 50 as my invention, I have signed my name in presence of two subscribing witnesses.

OTTO FRICKE.
